UNITED STATES PATENT OFFICE

HARRY W. BOLENS, OF PORT WASHINGTON, WISCONSIN

CHAIR IRON

Application filed October 29, 1930. Serial No. 491,955.

This invention pertains to chair irons and particularly to an iron fabricated from sheet steel or other suitable material.

The invention has primarily for its object to improve the foregoing structures by reducing height, thus accommodating the iron to heavy upholstered seats without increasing the height of the chair; by the provision of a novel form of stop to limit tilting action of the seat spider in one direction; and by the provision of means to deaden or prevent the transmission of sound from one member to another.

Incidental to the foregoing, a more specific object resides in the provision of an iron of the foregoing character having a high pivoted seat spider and widely spaced tension springs, whereby the iron may be set well down upon the spindle.

A more specific object resides in the provision of sound deadening or insulation pads disposed between the members from which the iron is fabricated, thus eliminating accentuation and transmission of squeaking noises originating from the action of the tension springs.

A still further object resides in extending the seat saddle downwardly to receive the spring tension adjusting means, and to engage one end of the spindle yoke to limit movement of the spider in the direction occasioned by the tension springs.

With the above and other objects in view, which will appear as the description proceeds, the invention resides in the novel construction, combination, and arrangement of parts substantially as hereinafter described and more particularly defined by the appended claims, it being understood that such changes in the precise embodiment of the herein disclosed invention may be made as come within the scope of the claims.

In the accompanying drawing is illustrated one complete example of the physical embodiment of the present invention constructed according to the best mode so far devised for the practical application of the principles thereof.

In the drawing, Figure 1 is a vertical longitudinal section through an iron construct-

ed in accordance with the present invention;

Figure 2 is a longitudinal plan section taken on the line 2—2 of Figure 1; and

Figure 3 is a vertical transverse section taken on the line 3—3 of Figure 1.

Referring now more particularly to the accompanying drawing, the numeral 1 designates a conventional spindle which carries a yoke 2, the latter being preferably formed in the shape of a cup within which the tension means hereinafter described is housed.

The yoke 2 is secured to the head of the spindle 1 by means of a transverse arched strap 3 secured upon the bottom of the yoke in any suitable manner and having its arched portion engaged with the head of the spindle by riveting or other suitable means, it being noted particularly in Figures 2 and 3 that the arched portion of the strap 3 is centrally positioned with relation to the yoke.

Pivottally mounted on the yoke 2 is a seat spider 4 comprising a pair of angle spider arms 5 secured upon a saddle 6 preferably by riveting or bolting the same thereto, the reason for which will be later explained.

The saddle 6 is provided at its front end with a depending apron 7, both the apron and the saddle having longitudinal side flanges 8 adapted to straddle the yoke 2, which flanges serve to insure proper alignment between the spider and yoke and also effect the desired reenforcement for both the saddle and its depending apron. Due to the somewhat excessive width of the saddle 6, in some instances it may be desirable to transversely reinforce the same, in which a reinforcing strap 9 is secured transversely to the inner side of the apron. Also, vertical webs 10 may be welded or otherwise attached to the inner faces of the saddle and apron to further reinforce the same.

As best shown in Figures 1 and 3, the spider 4 is pivotally mounted upon the yoke by means of a pintle bolt 11 passing through the flange of the spider arms, the saddle, and the sides of the yoke 2 adjacent their upper edges, thus affording a high pivot point with relation to the spindle which, because of the manner of attaching the yoke to the spindle, provides an iron of reduced height, whereby

the same is applicable to a heavily upholstered seat without increasing the height of the chair.

The front end of the yoke 2 is provided with a vertically elongated slot 12, while the apron 7 has a corresponding slot 13 through which a tension adjusting bolt 14 passes. Mounted upon the inner end of the bolt 14 is a spring retainer 15 extending transversely of the yoke and provided with seats 16 for the reception of the spaced tension springs 17, the opposite ends of which springs engage spring seats 18 riveted or otherwise secured to the front wall of the yoke 2.

15 A fulcrum strap 20, mounted on the outer end of the adjusting bolt 14, engages a depression in the front of the apron to allow relative movement between the bolt and apron when the spider is tilted. A hand wheel 19, threaded on the outer end of the bolt, serves to regulate tension upon the spring 17.

In fabricating or connecting the various members comprising the iron, it will be noted in all instances that pads or washers 21 of composition or sound deadening material are positioned between the engaging surfaces of the adjacent members, thus preventing the usual squeaking noises, resulting from action of the springs, from being accentuated or transmitted from one member to another, which feature is highly desirable in offices utilizing a considerable number of chairs.

In operation, it will be quite apparent that the spring 17 will permit the spider 4 to be tilted rearwardly upon its pintle 11 against the tension of the springs, in which action the saddle 6 engages the top edges of the sides of the yoke 2 to limit movement of the spider in that direction, while the apron 7 engages the front of the yoke to limit movement occasioned by the tension of the springs. Thus, it will be seen that the apron serves two purposes, namely, as a stop, and to carry the tensioning means.

It will also be noted, particularly in Figures 2 and 3, that the tension springs are spaced sufficiently apart to enable the arched yoke to be positioned therebetween, which allows the yoke to be secured well down on the spindle, which reduces the height of the iron from the floor, and as heretofore explained, allows an exceedingly heavy upholstered seat to be used without unduly increasing the height of the chair.

It will further be appreciated that an exceedingly simple and rigid structure has been provided, in which the parts of the iron, although formed of sheet material, are thoroughly reenforced to provide the desired strength or rigidity necessary because of the strain to which they are subjected.

It has also been found from actual experience that through the method of insulation employed between the various parts

from which the iron is fabricated, that the squeaking usually resulting from the action of the coiled springs is muffled or deadened, in that the same cannot be transmitted from one member to another, thus accentuating the noise.

I claim:

1. A chair iron comprising a stationary member, a seat spider pivotally connected to said stationary member adjacent its upper edge, resilient means for resisting tilting action of said seat spider, said means including a pair of spaced springs, an arched strap secured to said stationary member and having its arched portion positioned between said springs, and a spindle having its head secured to the arched portion of said strap. 70

2. A chair iron comprising a spindle, a cup-shaped yoke secured to said spindle, a seat spider including a saddle having longitudinal spider arms secured thereto, means pivotally connecting the saddle to the yoke, an apron depending from said saddle for engagement with the front of said yoke, a bolt passing through said apron and the front of said yoke, a transverse spring retainer carried on the inner end of said bolt, spaced springs seated on said retainer and engaging the front of said yoke, and a hand wheel engaging said apron for adjusting said bolt. 75

3. A chair iron comprising a spindle, a yoke secured to said spindle, a seat spider including a saddle having longitudinal spider arms secured thereto, said saddle being pivotally connected to said yoke adjacent its upper edges, an apron depending from said saddle for engagement with the front of said yoke, a bolt passing through said apron and the front of said yoke, a transverse spring retainer carried on the inner end of said bolt, spaced springs seated on said retainer and engaging the front of said yoke, and a hand wheel engaging said apron for adjusting said bolt. 80

4. A chair iron comprising a spindle, a yoke secured to said spindle, a seat spider including a connecting saddle having a vertical web for engagement with the front of said yoke, said seat spider being pivotally mounted on said yoke adjacent its upper edges, a bolt passing through said web at the front of said yoke, a transverse spring retainer carried on the inner end of said bolt, spaced springs seated on said retainer and engaging the front of said yoke, and a hand wheel engaging said web for adjusting said bolt. 85

In testimony that I claim the foregoing I have hereunto set my hand at Milwaukee, in the county of Milwaukee and State of Wisconsin.

HARRY W. BOLENS.
